UNITED STATES PATENT OFFICE

2,613,082

GAS MANIFOLD AND VALVE FOR ANALYZING
GAS MIXTURES

Lloyd V. Guild, Pittsburgh, Pa.

Application March 15, 1949, Serial No. 81,516

1 Claim. (Cl. 277—60)

1

This invention relates to new and useful improvements in apparatus for analyzing gases, and it is among the objects of the invention to provide a gas manifold and valves which shall be of simple construction and accurate in use.

The invention will become more apparent from a consideration of the accompanying drawings, constituting a part hereof, in which like reference characters designate like parts, and in which

Fig. 1 a front elevational view of a modified form of gas analysis apparatus;

Fig. 2 a top plan view of the device shown in Fig. 4;

Fig. 3 a front elevational view, broken away, of a portion of the manifold of the gas analyses apparatus; and

Figs. 4 and 5 cross-sectional views, respectively, of a special type of valve employed for controlling the gas flow in the manifold.

With reference to the several figures of the drawing, numeral 1 designates a frame having a valved manifold section 2 at the top, a cross partition 3 for supporting pipettes 4, 5, 6 and 6a, below which is mounted a bracket 7 for supporting a washing bottle 8 having an inlet 9 and an outlet 10, the latter being provided with a valve 11.

The partition 3 extends downwardly at 3a to form an elongated chamber for a graduated tube 12 which is used for measuring the volumes of the gas samples to be tested. The graduated tube or burette 12 is immersed in a water bath confined in a transparent cylinder 13 closed at the ends with rubber stoppers 14 and 15, respectively. The purpose of the water bath is to maintain the gas in the burette 12 at a constant temperature and therefore constant volume. Connected to the bottom of the burette 12 is a flexible hose 16 leading to a vessel 17 filled with a confining liquid, such as water or salt solution 18, for the purpose of forcing gas in and out of the burette 12 and for obtaining a set gas pressure.

The manifold 2 represents the control valves and gas distributing system and is better understood in connection with Figs. 3 to 5 of the drawings, which in Fig. 4 illustrates the manifold 2 as consisting of cast metal parts 19 and 20, the latter having depending cylindrical portions 21 for connection with the pipettes by flexible tubing 22, Fig. 1. The member 20 is provided with a channel 23 communicating with a gland 24 with the connections 21. The flow of gases through the glands 24 from the measuring burette to the pipettes and the washing fluid is controlled by valves consisting of a flexible rubber or neoprene strip 25 which is displaced as shown in Fig. 5 by a plunger 26 operable in a cylindrical bore 27 of the metal casting 19, the plunger being actuated by a thumb screw 28. Coil springs 29 are provided to prevent seating of the strip 25 when the plunger 26 is in open

2

position, as shown in Fig. 4. Where the glands 24 open into the meeting channels 23, a special valve seat 30 is provided which effectively seals off the opening when the valve is closed, without, however, obstructing the meeting channel passage 23, as is clearly shown in Fig. 5.

The valves in Fig. 1 of the drawing are designated by the reference characters 31, 32, 33, 34, 35a and 36, respectively, by means of which gas from burette 12 may be diverted to any of the pipettes 4, 5, 6 or 6a.

It is evident that by the use of a manifold having a meeting channel common to all of the valves and by the employment of the plunger or cylinder valve with a yieldable strip, leakage and breakage incident to the use of the conventional form of glass cock valves is eliminated.

Although one embodiment of the invention has been herein illustrated and described, it will be evident to those skilled in the art that various modifications may be made in the details of construction without departing from the principles herein set forth.

I claim:

25 In apparatus for analyzing gas mixtures, a valved manifold comprising an elongated body portion having a plurality of depending cylindrical members with glands communicating with a common meeting channel, said channel having cylindrical recesses concentric with the glands of said depending members, a second body portion of complementary dimensions to said first-named body portion, and a resilient strip disposed between the abutting faces of said portions, the second-named body portion having cylindrical portions in register with the cylindrical recesses of the first-named body portion, a cylinder in each of said portions and adjusting screws abutting the ends of the cylinders whereby upon displacement of the cylinders, portions of the resilient strip are displaced in the recesses of the first-named body portion to effectively seal the gland with which it is in register, said first-named body portion being counterbored in the gland passage for receiving springs to restore the flexible strip to its normal open position when the screw acting on the cylinders is retracted.

LLOYD V. GUILD.
